FIG. 2

FIG. 3

INVENTOR
Harry S. Hays,
BY Walter N. Haskell
his ATTORNEY

UNITED STATES PATENT OFFICE.

HARRY S. HAYS, OF MOLINE, ILLINOIS.

INTERNAL-COMBUSTION ENGINE.

Application filed March 19, 1925. Serial No. 16,830.

My invention relates to improvements in internal combustion engines, and has more special reference to that class of said devices in which the gas intake and exhaust operations are under the control of a rotary valve. One of the purposes thereof is to provide a quiet, smooth-running engine, which will operate with a minimum amount of vibration.

Another object of the invention is the provision of a valve mechanism of the type mentioned, and parts appurtenant thereto, of such a construction that the same will form the unitary head of an engine block of a conventional pattern, so that the invention can be readily substituted for the usual head of such engine, and fully take the place thereof.

Another feature of the invention consists in a novel arrangement of cooling chambers, whereby the excessive heat generated in the cylinders and combustion chambers may be reduced and neutralized.

Another object thereof is the provision of a cooling compartment on the interior of the rotary valve, and surrounding the combustion chamber, so as to prevent the over-heating of such parts.

Another advantage of the invention consists in having the combustion head seated loosely in the upper end of the cylinder bore, so that the same will adapt itself readily to such cylinder. The combustion head is also mounted in such a way as to be capable of adjustment with reference to the cylinder bore, or cylinder head bore, as the case may be. Said combustion head is also provided with a sealing means, between such head and the valve, to prevent the escape of vapor charges therethrough, under compression, or of the explosive gases, under combustion.

The above-named, and other features and advantages of the invention will more fully appear from the following specification, taken in connection with the accompanying drawings, in which:

Fig. 1 is a vertical cross-section of the invention, as it appears when embodied in a motor.

Fig. 2 is a horizontal cross-section, on the broken line 2—2 of Fig. 1.

Fig. 3 is a perspective view of the valve 21, detached.

The reference number 1 indicates an engine cylinder of usual construction, below which is shown a fragmentary portion of a crank-shaft casing, in which is mounted a crank-shaft 3, connected by a rod 4 with a

piston 5, movable in the cylinder 1. Said cylinder is enclosed within a water-jacket 6.

Mounted above the cylinder 1 is a head formed of two parts 7 and 8, provided with means for detachable connection, not shown in the drawings. Said head is also detachably secured to the cylinder-block by means of usual fastening devices, not shown. In the part 7 is a water compartment 9, and in the part 8 is a water space 10, communicating with the space 9 through passages 11 and 12. Centrally of the part 8 is a cylindrical opening 13, within which is supported a combustion head 14, by means of bolts 15, secured in the part 7. Within the head 14 is a water space 16, connected with the compartment 9 through openings 17. Centrally of the head 14 is a combustion chamber 18, the walls of which converge upwardly to a threaded opening in which is installed a spark-plug 19, the head 7 having an opening 20 to permit the placing or removal of such plug.

Between the combustion head 14 and inner wall of the opening 13 is a space within which is rotatably mounted a cylindrical valve 21, having in its walls a series of equally spaced ports 22, three of such ports being shown in the present embodiment. Said ports are adapted for successive registry with a fuel intake passage 23 and exhaust passage 24 in the wall of the part 8 of the cylinder head. Said ports also communicate inwardly through an opening 25 in the head 14 with the combustion chamber 18 therein.

On the upper end of the valve 21 is a gear-rim 26, the teeth of which are in mesh with a worm drive gear 27 on a shaft 28 rotatably supported in an opening 29 extending through one side of the head. Said shaft is provided with a central bore 30 for lubricating purposes, said bore communicating through a perforation 31 with the threads of the worm 27. Movement of the crank-shaft 3 may be imparted to the shaft 28 in any suitable manner, as for instance, by means of a belt or chain as indicated at 32, connecting a wheel 33 on the shaft 28 with a similar wheel 34 on the crank-shaft.

On the outer face of the head 14 is an annular recess to accommodate a seal ring 35, which is held immovably in position, and is provided with an opening 36 in one of its sides, coinciding in position with the passage 25. An auxiliary packing ring 37 may be provided, if desired, near the lower end of the head 14.

The water-spaces in the head section 8 are in communication with the water-jacket 6 by means of openings 38 connecting the same, and the water-jacketing may also extend between and around the passages 23 and 24, as shown at 39. (Fig. 2.) The various water spaces extend throughout the length of the engine block, as indicated in connection with the compartment 10 in Fig. 2, the desired 10 number of cylinders being positioned therein at regular intervals.

In the operation of the valve 21 one of the ports therein is brought into line with the intake passage 23, and a charge of vapor admitted to the cylinder. Following the compression stroke and explosion of the gas the next succeeding port in said valve is brought into registry with the exhaust passage 24, as shown in Fig. 2. In the continued movement 20 of the valve this port is the next one to admit a charge of gas through the intake 23. In the usual four-cycle type of engine, with the present valve arrangement of three ports, there would necessarily be six revolutions of 25 the crank-shaft to one complete rotation of the valve, which can be provided for in the worm-gear drive mechanism.

It will be observed that the valve 21 is not only fully enclosed, so as to be as little exposed to the heat radiation as possible, but it is also provided with water-cooling means both within and without. There is therefore no danger of the valve expanding unduly or becoming warped through the action of the 35 heat resulting from the succeeding explosions of gas.

The invention is made of such form and dimensions as to render the same readily attachable to engine-blocks of an established pattern. It can also be embodied in an engine at the time of building thereof, if desired. When separately made it can be used for re-

placing the cylinder-heads of other formations, as hereinbefore mentioned.

By the use of the seal-ring 35 the escape of 45 gases between the head 14 and valve 21 is fully prevented.

In case the combustion head 14 is not in axial alignment with the cylinder 1, by turning one or other of the screws 15 it can be 50 made to conform thereto, so as to fit properly in the end of the cylinder.

There has been shown and set forth herein the preferred embodiment of the invention, it being understood that changes can be made 55 in the form and arrangement of the parts thereof, by those skilled in the art to which it pertains, without departing from the spirit of the invention, as set forth and claimed herein.

What I claim, and desire to secure by Letters Patent, is:—

A device of the class described, comprising a cylinder head formed of two parts having intercommunicating water-spaces, gas intake 65 and exhaust passages extending through one of said parts into the center of said head, a hollow combustion head supported in said last-named part, and provided with an opening into said intake and exhaust passages, and 70 having a central opening the walls of which converge upwardly to a spark-plug seat, means for adjustment of said combustion head with reference to the end of a cylinder with which the head is connected, a cylindrical valve rotatably mounted between said combustion head and cylinder head, provided with ports for successive register with said intake and exhaust passages, and a seal ring 75 between said valve and combustion head, having an opening coinciding with the opening in said combustion head.

In testimony whereof I affix my signature.
HARRY S. HAYS.
